UNITED STATES PATENT OFFICE.

JOSEPH H. LYNCH, OF ASBURY PARK, NEW JERSEY.

LAUNDRY-CHECKING DEVICE.

Application filed December 22, 1926. Serial No. 156,365.

This invention relates to a checking device whereby individual packages of laundry may be kept associated together in individual groups.

5 The invention comprises individual group supports, each support having means for carrying individual identification checks or tags from which are suspended articles of laundry, the checks and the supports having individual lock and key characteristics whereby the checks of any one group will fit only the support to which they appertain.

An embodiment of the invention is illustrated in the accompanying drawing, in 15 which:

Figure 1 is a perspective view of a laundry support and checks applied thereto.

Figure 2 is a plan view of the same, and 20 Figure 3 is a cross-section on line 3-3 of Figure 2.

The support is made essentially of two angle pieces of metal shown at 1, that are held at a certain distance apart by cross pieces 2 in such a way as to leave a slot 3 between the lower edges of the angles. The angles form a stiff guide or support into which properly designed checks may be assembled. The front cross piece 2 has an opening therethrough of a particular shape 25 which corresponds in contour to the upper part of a check or tag 4 to which articles of clothing may be attached by means of safety pins 5. The checks 4 are designed to slide on the guides 1 and have a restricted 30 neck portion 6 adapted to fit slidingly in the slot 3 between the opposing edges of the guides. In order to keep the check or tag 35 from being turned sidewise, in which case they might drop through the slot 3, they are provided with a thickened neck where they 40 pass through the slot, or with a projection at this point as shown at 7 in Figure 2. The supports 1 may have brackets 8 at the rear end suitable for attachment to a wall. 45 It will be understood that there will be a number of such supports arranged along the wall, each support being characterized by an individual orifice in the end-piece 2, and that for each support, there will be a number of checks or tags 4 having the same contour on their upper end and that all those tags belonging to one support will all carry 50 same number. Thus, the articles of laundry

belonging to one customer will be grouped together by being identified by their identification checks or tags which tags will remain with the pieces of laundry in their passage through the washing and ironing processes and will, when finally hung up on the holders, be necessarily kept in their proper groups. It will be seen that the angles make a strong simple and cheap form of support and that the check is of the required flatness to render it capable of passing through the laundering machines without injury either to itself or to the clothing. The guides may be formed of channel bars instead of angles or they may be joined by a web at the top, the only essential being that the slot shall be uniform in width with the whole length of the holder and that there shall be in connection with the guide portion other portions at an angle thereto to insure proper rigidity.

I claim:

1. In a system of identification tags for laundry, the combination of a support having two parallel guiding rails spaced apart to form a slot between them, laundry checks having a constricted neck adapted to slide 80 between the guides and an end-piece secured to the guides having an opening therethrough, the contour of said opening being individual to a contour on the check.

2. In a system of identification tags for laundry, the combination of a support having two parallel guiding angles spaced apart to form a slot between them, laundry checks having a constricted neck adapted to slide 85 between the guides and an end-piece secured to the guides having an opening therethrough, the contour of said opening being individual to a contour on the check.

3. In a system of identification tags for laundry, the combination of a support having two parallel guiding rails spaced apart to form a slot between them, laundry checks having a constricted neck adapted to slide 90 between the guides and an end-piece secured to the guides having an opening therethrough, the contour of said opening being individual to a contour on the check, the neck of said check having free play endwise in the slot but restricted play around its vertical axis.

JOSEPH H. LYNCH.
